UNITED STATES PATENT OFFICE.

GARNETT SNIDER, OF BRUCES MINES, ONTARIO, CANADA.

ELECTRIC-LAMP SOCKET.

1,327,496.

Specification of Letters Patent.

Patented Jan. 6, 1920.

Application filed September 22, 1917. Serial No. 192,785.

To all whom it may concern:

Be it known that I, GARNETT SNIDER, a subject of the King of England, residing at Bruces Mines, in the Province of Ontario, 5 Dominion of Canada, have invented new and useful Improvements in Electric-Lamp Sockets, of which the following is a specification.

This invention relates to an electric lamp 10 socket, and one of the objects is to provide means whereby a lamp may be secured to the socket more readily than when employing a socket of usual construction having a continuous shell, the walls of which are 15 provided with a screw thread.

A further object is to provide a socket 20 which will positively engage the threaded base of a lamp when said lamp is merely forced or thrust into the socket and given a slight twist, thereby avoiding the necessity 25 of turning the lamp a number of times for causing the full engagement of the contact elements.

A further object is to provide a socket in 30 which one of the terminal members comprises a plurality of segmental portions, the walls of which are formed with screw threads for engaging the threads of the lamp, these segmental members being connected by a transversely extending member 35 retained in position by the main body portion of insulation, that is by the porcelain block, or the separate members constituting said block.

A still further object is to provide a socket 40 of the type specified in which the segmental members are resiliently held in position with reference to each other, for the purpose of firmly gripping the base of the lamp.

In the drawings:

Figure 1 is a view in vertical section.

Fig. 2 is a view in elevation of the porcelain block and the elements carried thereby for engaging the lamp.

Fig. 3 is a bottom plan view.

Fig. 4 is a perspective view of the lamp retaining members.

Fig. 5 is a transverse section through the block showing the device operated by the 50 spindle for making contact.

The main casing of the socket is designated 10 and the cap coöperating with the casing is shown at 12, the casing and cap being provided with an inner lining of insulating material as shown at 13 and 14. The por-

celain insulation includes a plurality of members 14' and 15, and the usual key 16 is mounted on a spindle 17 which latter includes an offset portion 18 coöperating with the U-shaped resilient device 20 which is 60 slidably longitudinally with reference to the spindle in view of its engagement by the offset portion and causes the movement of said U-shaped member into engagement with the contact member 21 carried by a device of 65 special construction mounted on the porcelain block and designed to be directly engaged by the threaded base of the lamp. When the member 20 is in engagement with the contact member 21 it is also in engagement with terminal 22, completing one side of the circuit. The other terminal is designated 24 and extends to the central portion of the socket as shown. In Fig. 5 element 20 is shown as having one prong (which is 70 normally the upper prong) bifurcated, for engaging elements 21 and 22. The other end engages an angle formed by offset 18, when the switch is open. Upon turning the spindle 17 through 180 degrees, the opposite side 75 of the offset portion will be engaged, and this side is reversely inclined, after a one-half revolution of the spindle, so that the tendency of the spring in expanding is to move toward the left in Fig. 1, and into position to close the switch. The split end of the spring is then moving downwardly along an abrupt incline. The offset portion is somewhat flattened.

The shell or socket proper which directly 80 engages the threaded portion of the lamp base comprises a plurality of members 25 and 26 of segmental form, these members having walls formed with screw threads for engaging the lamp base, and being connected 85 at their inner portions with a transversely extending member 28 which is carried by the body portion of insulation comprising the sections 14' and 15. Each section specified includes an upwardly extending member 29 having an undercut portion 30, the oppositely located sections forming by reason of the portions indicated, a transversely extending channel accommodating the connecting member 28 of the shell. This member 28 is of material sufficiently heavy to provide the necessary degree of resiliency for the segmental members 25 and 26, causing them to firmly engage the lamp base. The elements 25 and 26 are broader than the 100 105 110

member 28 but are not of sufficient extent to cause the edges thereof to meet, a space being provided at 30 and at 31 as shown.

The segmental members 25 and 26 may be outwardly flared to a slight extent as shown at 25' and 26', permitting the lamp to be promptly forced into position, full engagement being secured by giving the lamp a slight twist for casing the threads to operate.

What is claimed is:

1. In a device of the class described, a casing, a body of insulation inclosed thereby and including a plurality of sections, a shell for engaging the threaded base of the lamp and comprising a plurality of segmental members formed with threads, a transversely extending member connecting said segmental members, said sections of the body portion being provided with channeled portions oppositely located for receiving the transversely extending portion of the shell.
2. In a device of the class described, a

casing, a body portion of insulation inclosed thereby and including a plurality of sections, each section including a member extending from one end thereof and spaced from the corresponding member of the adjacent section when the sections are secured together, each of said members having an undercut portion, said portions forming together a channel extending transversely of the body portion and in the direction of the line of division between the sections, a shell for engaging the base of a lamp and comprising a plurality of segmental members the walls of which are provided with threads, and a transversely extending member of resilient material connecting the segmental portions and causing the latter to firmly engage the base of the lamp thrust longitudinally between said segmental portions, said transverse member being located within the channel.

In testimony whereof I affix my signature. 45
GARNETT SNIDER.
